America as represented by the Secretary of the
Navy

Application September 14, 1945, Serial No. 616,412

7 Claims. (Cl. 178—44)

1

My present invention relates in general to apparatus for eliminating high standing wave ratios in transmission line systems, and in particular to a series reactance transformer for use in a transmission line system having a frequency sensitive termination to provide a relatively constant input impedance to such a line over a relatively wide band of frequencies.

When it is sought to transmit electromagnetic energy of high frequency from a generator to a frequency sensitive load through a transmission line system, it is necessary that the frequency of operation be kept relatively constant if the impedance of the load is to remain relatively constant during transmission. Variations in the frequency may cause the load impedance to become inductive or capacitive depending upon the direction of variation. A variation in the load impedance will be reflected as a variation in the input impedance to the transmission line at the generator. This in turn is due to the fact that the variation in the load impedance with frequency changes causes high standing wave ratios in the transmission line. Such high standing wave ratios result in loss of power and frequently also in arc-overs in the transmission line, both of which are undesirable.

It is an object of my invention to provide a series reactance transformer for use in a transmission line which will preserve substantially unaltered over a wide band of frequencies the input impedance to a transmission line which has a frequency sensitive termination.

It is a further object of my invention to provide such an impedance matching transformer that will have no effect upon a tuned transmission line system when the system is operating at the resonant frequency for a frequency sensitive load.

It is a still further object of my invention to provide such a series reactance transformer that will be simple to construct in the ordinary transmission line of the coaxial or hollow wave guide type.

Other and further objects and features of my present invention will become apparent upon a careful consideration of the following detailed description when taken together with the accompanying drawing, the figures of which illustrate typical embodiments of the invention and the manner in which those embodiments may be considered to operate.

Fig. 1 illustrates in longitudinal section a series reactance transformer of my invention incorporated in a coaxial type of wave guide transmission line;

2

Fig. 2 illustrates in electrical scheme the equivalent circuit of the transformer of Fig. 1;

Fig. 3 is a graph showing the reactance curve of the inductive and capacitive members of the transformer of Fig. 1;

Fig. 4 illustrates in longitudinal section a transformer of my invention installed in a hollow wave guide; and

Fig. 5 illustrates in electrical scheme the equivalent circuit of the apparatus of Fig. 4.

Referring now to Fig. 1, a coaxial line 1 having an outer conductor 2, and an inner conductor 3 has affixed to the inner conductor a projection 4 extending longitudinally or axially with respect to the wave guide 1. The projection 4 is undercut at each end 5 and 6 in a direction parallel to the axis of the line 1 to form first and second short circuited transmission line sections or stubs 7 and 8 respectively between the projection 4 and the inner conductor 3 of the coaxial line 1. These sections are separated by a support 9 for the projection 4. The section of line contained between the projection 4 and the outer wall 2 has a lower impedance than the main line 1, having a lesser spacing between conductors than the said main line 1. The length of this section of lower impedance line is determined by the axial length of the projection 4, which length is preferably substantially equal to one-half or an integral number of half wave lengths of energy at the resonance or mid-band operative frequency. The projection 4 projects toward the outer conductor 2 a distance determined by the spacing required between these two members to prevent voltage breakdown, and further by desired impedance values in the short circuited sections 7 and 8. When the coaxial line 1 that is being used is not extremely small, the projection 4 may have an outer diameter as great as one-eighth of a wavelength of the energy being carried in the line 1.

The width and depth of each short circuited stub 7 or 8 are determined by the desired impedance values. The first stub 7 has a depth always greater than one quarter but less than one-half the length λ of a wave of energy therein at any frequency in the operative frequency band, while the second stub 8 has a depth always less than one quarter of the said wave length λ . The lengths of the stubs 7 and 8 may be so adjusted that these two elements form a series resonant circuit at the mid-band operative frequency, or the resonance frequency, as will be hereinbelow explained.

Referring now to Fig. 2, there is illustrated a transmission line system having a frequency sen-

sitive termination or load 12 of impedance Z_L . The transmission line 11 has an input impedance Z_0 . Between the points A and B are illustrated the equivalent elements of the transformer of my invention shown in Fig. 1. Since the shorter stub 8 is always less than a quarter of a wave length long this stub 8 will have the electrical effect of an inductance, and is therefore illustrated in Fig. 2 as an inductor 14. Likewise since the longer stub 7 is always greater than one quarter but less than one half a wave length long, this stub 7 will have the electrical effect of a capacitor, and is illustrated as a capacitor 15 in Fig. 2. It is to be noted that the inductor 14 and the capacitor 15 are in series with each other. The half wave section of line contained between the projection 4 and the outer wall 2 in Fig. 1 is in Fig. 2 a section of line 13 having a lower impedance Z_1 than the main line 11, located between the two reactive elements 14 and 15. A generator (not shown) will see an impedance Z_0 upon looking into the line 11.

In operation, my transformer is effective to cause the range through which the input impedance of the line 11 (or the line 1) would vary during a particular range of operative frequency variations to become smaller than the normal range of input impedance variation for the same amount of frequency variation. This bunching together of the input impedance limits within a frequency band may be considered to be accomplished in steps by placing first one and then the other of the stubs 7 and 8 in the line 1. By properly locating the transformer in the line 1 with respect to the termination or load, a point may be found such that the addition of a first reactance with one sense will cause a certain amount of bunching, and the addition of a second reactance with the opposite sense will cause still more bunching and at the same time match the line 1 to its load. The stubs 7 and 8 provide such first and second reactances. The desired bunching of input impedance variation limits may be had without effecting an impedance match between the line 1 and its load, it being an object of my invention only to maintain the said input impedance substantially constant.

In the case where the line 1 is matched to its load (or the line 11 to the load 12 in Fig. 2) the stubs 7 and 8 should preferably be series resonant at the resonance frequency for the line and load. The points 20 and 21 in Fig. 3 illustrate this condition, showing the reactances X_L of the shorter (inductive) stub 8 and X_C of the longer (capacitive) stub 7 as equal in magnitude and opposite in sense. These reactances will mutually cancel each other, so that the stubs 7 and 8 will be effectively not present in the line 1 at the resonance frequency.

During variation from the mid-band or resonance frequency, the reactances of the stubs 7 and 8 will become altered. With a frequency rise, these stubs become effectively longer, the lengths of higher frequency waves being relatively shorter. On the graph of Fig. 3, this corresponds to new frequency operating points 22 and 23 for a shorter operating wave length. The shorter (inductive) stub 8 will have a relatively larger inductive reactance X_L , and the longer (capacitive) stub 7 a relatively smaller capacitive reactance X_C . With a drop in frequency the stubs 7 and 8 become effectively shorter. The shorter stub 8 will then have a relatively smaller inductive reactance X_L , while the longer stub 7 will have a relatively larger capacitive reactance X_C .

X_C , as illustrated at the corresponding lower frequency operating points 24 and 25 respectively in Fig. 3.

The effect of the hereinabove discussed changes in the natures of the circuit elements 7 and 8 of the transformer of my invention during frequency variations is to counterbalance simultaneous changes in the nature of the impedance of the load so as to preserve substantially unaltered the input impedance of the line 1 over a band of operating frequencies. The half wave line section 13 will become effectively shorter or longer than a half wave in the presence of frequency variations in the same manner as the stubs 7 and 8. When this section 13 has a length other than exactly one half a wave length, its effect upon the transmission line 1 will be to multiply the impedance of the line 1 at the point of entering the half wave section, which impedance may have a value $R+jX$, by a quantity

$$\frac{Z_0}{Z_1} \text{ or } \frac{Z_1}{Z_0}$$

depending upon the direction of frequency shift. This effect is small compared to the effect of the stubs 7 and 8, and may be neglected.

Thus it may be seen that, when properly located in a line having a frequency sensitive termination, my transformer will maintain the input impedance to the line, as seen for example from a generator, substantially constant over a relatively wide range of frequencies. In the event that a load having the opposite frequency characteristics from one with which my transformer may be in use is used, the transformer may be reversed in the line 1 or moved along the line a distance of the order of one half a wave length and satisfactory operation will be therewith obtained.

The limits of the band of frequencies over which the transformer of my invention will operate satisfactorily are reached when either of the two short circuited stubs 7 or 8 becomes exactly one quarter of a wave length long. In these limits one or the other of these stubs 7 or 8 will have substantially infinite impedance, as may be readily appreciated by reference to the graph of Fig. 3. An infinite impedance in series with the transmission line has the effect of opening the transmission line circuit. Thus at a certain frequency above the mid-band frequency, the shorter stub 8 will be exactly one quarter of a wave length long, and become effectively an infinite impedance in series with the line 1, while at another frequency below the mid-band frequency the longer stub 7 will be exactly one quarter of a wave length long, and become effectively an infinite impedance in series with the line 1.

Fig. 4 illustrates a transformer of my invention incorporated in a hollow wave guide transmission line 50, having opposite walls 51 and 52 and an internal spacing D between said walls. The transformer of my invention is installed in the guide 50 on the opposite inner surfaces of these walls 51 and 52, one or more projections 53 and 54 being affixed on said opposite inner surfaces and projecting toward each other into the wave guide 50. The projections 53 and 54 extend axially or longitudinally with respect to the wave guide 50 and are substantially parallel to each other. Similarly to the projection 4 in the apparatus of Fig. 1 the projections 53 and 54 form a second wave guide section having an internal spacing d , which section corresponds to

the half wave transmission line section 13 of Fig. 2. The projections 53 and 54 are substantially one-half the length of a wave in the wave guide section bounded by them of energy at the mid-band operative frequency. Also, in the same manner as in the case of the projection 4 of the apparatus of Fig. 1, the ends of the projections 53 and 54 are undercut to form short, and long, short-circuited transmission line stubs 55 and 56, respectively, between each projection 53 or 54 and the neighboring wall 51 or 52 respectively. A pair of stubs 55 and 56 are separated from each other by a support 57 for each projection 53 and 54. The shorter stubs 55 are, as in the case of the apparatus of Fig. 1, always less than one-quarter of the length λ_s of a wave therein at any frequency in the operative frequency band, while the longer stubs 56 are always greater than one-quarter but less than one-half of the length λ_s of such a wave. The outermost distance a projection 53 or 54 extends from the inner surface of the wall 51 or 52 respectively to which the projection is affixed is again preferably determined by the impedance considerations in the stubs 55 and 56, and the spacing at which voltage breakdown will take place between the two projections 53 and 54. It is satisfactory to space each of the projections 53 and 54 inwardly a distance substantially equal to one-sixteenth of the length of a wave of energy in the wave guide 50. Thus the cross-sectional spacing d of the half-wave length section of the line bounded by the two projections 53 and 54 may for example be substantially $\frac{1}{8}$ as great as the cross-sectional spacing D between the walls 51 and 52 of the wave guide 50.

Because of the above mentioned ratio between the spacings D and d it can be reasonably predicted that the half wave length section of guide bounded by the projections 53 and 54 will not become a wave guide beyond cut-off. For example in the case where the wave guide 50 is a cylindrical wave guide having a diameter D large enough to permit the passage of the TM_{01} mode but small enough to inhibit the passage of the TE_{21} mode, the diameter D will desirably be slightly less than $.97\lambda$, where λ is the wave length of energy being carried in the wave guide 50. A small diameter d which is $\frac{1}{8}$ of $.97\lambda$ would be approximately $.85\lambda$. However, the small diameter d would have to be reduced to $.76\lambda$ before the TM_{01} mode were totally inhibited. Thus it can be seen that the transformer of my invention can be placed in a cylindrical wave guide without interfering with a normal mode of operation of that wave guide. Those skilled in the art will realize that the transformer of my invention may be placed inside other forms of wave guides without substantially interfering with the normal mode of operation of such wave guides.

Referring now to Fig. 5, it is apparent that the apparatus of Fig. 4 is similar in nature to that of Fig. 1. The load 12 having an impedance Z_L may be placed at one end of the line 91 and the other end of the line 90 connected to a generator (not shown). The shorter and longer short-circuited transmission line stubs 55 and 56 on the upper wall 51 are represented by inductive and capacitive circuit elements 14 and 15 respectively, while those on the lower wall 52 are represented by similar circuit elements 14' and 15' respectively. The one-half wave length section of line contained between the two projections 53 and 54 may be represented by a half-wave line section 93. Inasmuch as the elements 14' and 15' are

merely duplicates of the corresponding elements 14 and 15, these elements may be lumped together with their respective opposites to yield in effect, the circuit of Fig. 2. A further analysis of the apparatus of Fig. 4 in accordance with the circuit of Fig. 5 can thus be seen to be substantially identical to the analysis of the apparatus of Fig. 1. The apparatus of Fig. 4 functions in substantially the same manner as the apparatus of Fig. 1 when installed in a wave guide transmission line system, with one end of the guide 50 connected to a generator (not shown) and the other end connected to a load having an impedance characteristic that is frequency sensitive.

Although I have shown the transformer of my invention having short-circuited transmission line stubs that are respectively less than and greater than one-quarter of a wave length long and projections comprising those stubs which are substantially one-half wave length long, it is to be understood that the aforesaid projections, such as for example the projection 4 in the apparatus of Fig. 1 may be any integral number of half-wave lengths long. Likewise the short circuited stubs 7 and 8 of Fig. 1 or corresponding stubs 55 and 56 of Fig. 4 may be made in the neighborhood of three-quarters of a wave length long, or any odd number of quarter-wave lengths of energy in those stubs. Therefore it is to be understood that my invention is not to be limited except as may be required by the prior art and spirit of the appended claims.

I claim:

1. A broad-banding matching transformer for use in coaxial transmission lines comprising, a first coaxial transmission line having an inner and an outer conductor, and an axially extending projection coaxially affixed to said inner conductor and projecting toward said outer conductor a portion of the distance between said conductors to form a section of a second coaxial transmission line between said projection and said outer conductor, the axial length of said projection being substantially equal to an integral number of half wave lengths in said second coaxial line of energy at the mid frequency of the operative frequency band, said projection being undercut at each end in an axial direction to form first and second similar short circuited transmission line stubs between said projection and said inner conductor, said first stub being of a length always less than one quarter of a wave length therein of energy at any frequency in said operative frequency band, and said second stub being of a length always greater than one quarter but less than one half of said last mentioned wave length.

2. A broad-banding matching transformer for use in hollow wave guides comprising, a first hollow wave guide, and one or more axially extending projections affixed on opposite inner walls of said wave guide and projecting toward each other a portion of the distance between said walls to form a section of a second wave guide between said projections, the axial length of said projections being substantially equal to an integral number of half wave lengths in said second wave guide of energy at the mid frequency of the operative frequency band, said projections being each undercut at each end in an axial direction to form first and second similar short circuited transmission line stubs between each of said walls and the thereunto affixed projection, said first stub being of a length always less than one quarter of a wave length therein of energy at any frequency in said operative frequency band, and said second

stub being of a length always greater than one quarter but less than one half of said last mentioned wave length.

3. A broad banding transformer for use in transmission line systems comprising an open ended transmission line section of over-all length substantially equal to an integral number of half-wave lengths of energy therein at a predetermined frequency positioned within said transmission line, said section being formed to be capacitively reactive at one end thereof and inductively reactive at the other end thereof.

4. A broad banding transformer for use in a transmission line comprising, a section of over-all length substantially equal to an integral number of half-wave lengths of energy therein at a predetermined frequency positioned within said transmission line, said section having annular openings at one end thereof coaxial with said section and of a depth shorter than a quarter-wave length of said energy therein at said predetermined frequency, and having annular openings at the other end thereof of a depth greater than a quarter-wave length of said energy therein at said predetermined frequency.

5. Apparatus for maintaining the input impedance of a transmission line having a frequency sensitive termination substantially constant throughout a band of frequencies deviating from a mid-frequency comprising, a conducting structure positioned within said transmission line and cooperating therewith to form an open-ended transmission line section having a length substantially equal to a half-wave length at said mid-frequency, said structure being undercut at each end to a depth in a direction longitudinally of said transmission line to provide a capacitive reactance in series with said transmission line at one end of said section and an inductive reactance in series with said transmission line at the other end of said section, said reactances being series resonant throughout said band of frequencies.

6. A broad-band impedance matching transformer for use in a transmission line comprising, a conducting structure positioned within said transmission line and arranged to form an open-

ended transmission line section of overall length substantially equal to an integral number of half-wave lengths of energy at the mid-frequency of said band having an impedance smaller than the impedance of said transmission line, said structure being undercut at each end in a direction longitudinally of said transmission line to form first and second similar short circuited transmission line stubs between said transmission line and said structure, said first stub always being shorter than one-quarter wave length of energy therein at any frequency in said band of frequencies, and said second stub being of a length always greater than one-quarter but less than one-half of said last-mentioned wave length.

7. A broad-band impedance matching transformer for use in a hollow wave guide system comprising, a section of hollow wave guide, and a pair of projections secured to opposite inner walls of said wave guide and extending axially thereof, said projections extending toward each other and forming an open-ended transmission line section having a length substantially equal to an integral number of half-wave lengths at the mid-frequency of said bands, said projections being each undercut at each end in an axial direction to form first and second similar short-circuited transmission line stubs between each of said walls and the thereunto secured projection, said first stub always being shorter than one-quarter of a wave length of energy therein at any frequency in said band, and said second stub being of a length always greater than one-quarter but less than one-half of said last-mentioned wave length.
